UNITED STATES PATENT OFFICE.

GEORGE M. DOERSCH, OF CENTREVILLE, WISCONSIN.

BUNG AND BUSHING.

SPECIFICATION forming part of Letters Patent No. 426,115, dated April 22, 1890.

Application filed November 22, 1889. Serial No. 331,150. (No model.)

To all whom it may concern:

Be it known that I, GEORGE M. DOERSCH, of Centreville, in the county of Manitowoc and State of Wisconsin, have invented new and useful Improvements in Bungs and Bushings; and I do hereby declare the following to be a full, clear, and exact description of said invention, reference being had to the accompanying drawings, and to the letters of reference marked thereon, which form a part of this specification.

In the drawings, Figure 1 is a top or outside view of my improved bung and bushing. Fig. 2 is a transverse section through the bung and bushing on line 2 2 of Fig. 1, showing also the removable handle, by the aid of which the bung is turned down to its seat. Fig. 3 is a transverse section on the line 2 2 of Fig. 1 of the bushing forming a part of the bung, 20 showing the interior wall of the bushing on one side. Fig. 4 is a perspective view of a portion of the handle. Fig. 5 is a central section of a modified form of bung.

The bushing A is constructed of metal, and 25 is provided with a screw-thread B on the periphery of the part that is intended to enter and be fixed in the wall of a barrel, and an outwardly-projecting flange C is provided, which projects out over the edge of the 30 rounding wall of the barrel and rests thereon, forming a cover to the joint between the bushing and wall of the barrel. Near the inner end of the bung, entirely around on its inner surface, is an outwardly-facing ledge D, 35 adapted to receive the packing of the bung against its surface. Two inwardly-inclined or screw-formed grooves E E are cut in the inner surface of the bushing near its outer edge, each extending nearly one-half the distance around the bushing, and short channels F F are cut in the walls of the bushing from its outer surface directly to the outer ends of the grooves E E.

The bung consists of an inner plate or 45 keeper G, an outer plate H, a cover I, and a packing K, held together by a screw L, provided with a nut N.

The inner and outer plates G and H and the cover I are preferably constructed of metal 50 and are circular in form. The inner plate G is of such size as to enter within the bushing

A opposite the projection formed below the ledge D, and though preferably of metal may be of hard rubber or any other material not liable to be injured by the action of beer or 55 other liquids, of sufficient firmness to form a reliable keeper for the packing. The outer plate H is of such size as to fit loosely in the bushing above the ledge D, and the packing K, preferably formed of rubber disks 60 or rings of about the same size as the plate H, is secured to the inner surface of plate H, and near its outer edge is adapted to engage the ledge D in such manner that, being forced firmly down upon the ledge, as hereinafter 65 described, it forms an air and liquid tight joint therewith. The screw L passes loosely through the cover I and turns by its screw-thread into the plate H, extends loosely through the packing K and plate G, and is 70 provided with a nut N, turning thereon against the plate G, whereby the plate G is clamped tightly against the packing K, holding it firmly in position against the plate H. The cover I is rotatable on the screw L independently of the plate H, and is preferably provided with a bearing in the form of a ring T, 75 projecting slightly inwardly from its inner surface and adapted to bear against and travel on the plate H. This cover I is provided 80 with two opposite lugs M M, extending outwardly laterally from its periphery, which lugs are adapted to enter the grooves E E through the channels F F and to travel in and be guided by the walls of the grooves E E, as the 85 cover is rotated when the bung is in position in the bushing. The cover I is provided with an angled socket O, formed centrally in its outer surface, which socket is provided with an under-cut O', preferably in two sides of the 90 walls of the socket opposite each other. A handle P, having an angled head R of a size and form to fit the socket O and a laterally-projecting lug S, is adapted to be inserted in the socket, whereby conveniently to rotate 95 the cover I. The head of the handle is retained in its place in the socket O by the lug S, which enters the under-cut O'.

It will be understood that when the bung is placed in the bushing, the lugs M M being entered in the channels F F, by inserting the handle in the cover I and rotating it 100

the lugs M M will follow the grooves E E inwardly, as well as around the bushing, and the packing K will be forced tightly against the ledge D of the bushing, whereby an air and water tight joint will be made between the bushing and bung.

In the modified form of bung shown in Fig. 5 the cover I' is provided with a beveled inner surface to provide a limited bearing 10 against the plate H', and the ring T shown in Fig. 2 is omitted. The plate H' is constructed with a step U and a groove V around it near its inner surface, and a packing-ring K' is placed against the step and enters the groove 15 V, whereby it is held in place on the plate H'. This packing-ring K' serves the purpose of the disks K shown in Fig. 2, and this form of construction obviates the use of a keeper G and nut N. In this form of bung a screw 20 I' is used, which passes through the cover I' loosely and turns into the plate H', but does not extend beyond it.

What I claim as new, and desire to secure by Letters Patent, is—

The combination of a circular bushing having a ledge on and screw-formed grooves in its inner surface, a circular bung having a packing fitting against the ledge of the bushing, a thereto-attached rotatable cover having lugs adapted to enter and travel in the screw-formed grooves in the bushing, and also having a central laterally-faced socket provided with under-cuts in two directions opposite each other, a handle having a head faced laterally to fit the lateral faces of the socket 35 in the cover of the bung, and a foot or lug projecting laterally therefrom in one direction and adapted to enter either under-cut of the socket in the cover of the bung, substantially as described.

In testimony whereof I affix my signature in presence of two witnesses.

GEORGE M. DOERSCH.
